UNITED STATES PATENT OFFICE.

JOHN J. CHAPIN, OF NEW YORK, N. Y., ASSIGNOR TO CHAPIN PRODUCTS CORPORATION, OF NEW YORK, N. Y., A CORPORATION OF NEW YORK.

CAN OPENER.

Application filed August 26, 1921. Serial No. 495,629.

The primary object of the invention is the provision of a ready opener for tin cans and the like whereby the receptacle can be cut open without touching the receptacle as for instance where heated cans are to be opened quickly and easily without burning the hands of the operator.

A further object of the invention is the provision of a device for cutting a hole in a metal can leaving reamed or turned over edges at the severed portions so as to prevent cutting the fingers of the operator.

A still further object of the invention is the provision of a can opener operating on the principle of a pair of scissors giving great ease and speed to the operation of cutting the tin and reaming or turning over the edges thereof for gaining safe access to the interior of the can.

With these general objects in view the invention consists of the novel combination and arrangement of parts hereinafter more fully described in connection with the accompanying drawings and in which like reference characters designate corresponding parts throughout the several views.

In the drawings:—

Figure 1 is an elevational view of the can opener in its operative position upon the head or end of a can to be opened,

Figure 2 is an elevational view of one side of the device showing the gripping lever,

Figure 3 is a similar elevational view of the opposite side thereof showing the cutting lever,

Figure 4 is a perspective view of the plier joint of the gripping lever,

Figure 5 is a perspective view of the blade and abutment member of the cutting lever.

Figure 6 is an enlarged sectional view showing the removable blade taken upon lines 6—6 of Fig. 1, and

Figure 7 is a transverse sectional view taken upon line 7—7 of Figure 1 showing the friction joint.

Referring more in detail to the drawings my invention broadly consists of a gripping lever 10 having a plier joint 11 and a cutter lever 12 having a blade 13, the said levers being pivoted together by a rivet or pin 14 at one end and having operating handles 15 and 16 respectively, at their opposite free ends.

The gripping lever 10 is a double member formed of two sections 17 and 18 piv-

totally connected together at 11 and provided at adjacent points upon one side, designated the lower side of the can opener, with cooperating abutments 19 and 20 respectively. The said abutments are adjacent the inner side of the lever 10 toward the lever 12 and are adapted to open or separate a sufficient distance to receive the marginal bead 21 of a can such as 22 between the abutments 19 and 20 for grasping the bead 21 when exerting closing pressure upon the levers 10 and 12.

The opening of the plier joint 11 for separating the abutments 19 and 20 is limited by shoulders 23 at the opposite side of the lever 10 from the abutments 19 and 20. The abutment 19 of the lever section 17 for engaging the outer surface of the can 22 is of greater length than the abutment 20 upon the lever section 18 as the abutment 20 engages the inner surface of the bead or rim 21. It should be understood by those skilled in the art that although the gripping abutments function best when the can is provided with a flanged rim or bead about the periphery, nevertheless the device will operate to grip the peripheral edge of the can even though such a bead is not present, as in the case of a flush top can.

A pointed portion 24 adjacent the pivot 14 for the levers is carried by one of the levers such as the lever 10 being mounted upon the section 18 thereof and serviceable in making the initial opening in the end of the can 22 for the ready insertion of the cutting blade or knife 13 heretofore referred to, and also for opening the severed portion.

An abutment 25 upon the underside of the lever 12 spaced from the blade 13 and of greater length than said blade is adapted for engaging the outer surface of the can 21 when the blade 13 is in its cutting position through the end of the can and inwardly of the rim 21.

The blade 13 is removably positioned in a slot 26 opening at the inner side of the lever 12 while a small screw 27 is screw-threaded into the open end of the slot 26 for engaging the base 28 of the knife 13 and holding the knife rigidly to the lever 12.

An annular recess 29 in the pivoted ends of the lever 10 and 12 house a coil spring 30 for making a strong friction joint at the pivot 14.

The complete operation of the invention

will be fully understood from this detailed description thereof, the manner of applying the can opener being illustrated in Fig. 1 of the drawing. The knife 13 being positioned in the opening made by itself or the point 24 and the levers 10 and 12 separated, slight pressure exerted upon the handles 15 and 16 in the direction indicated by the arrows causes the abutments 19 and 20 to close 10 and grip the rim 21 rendering the lever 10 immovable for acting as an anchor in pulling the cutting lever 12 towards the lever 10. This produces a cutting of the end of the can by the knife 13, the length of cut being limited by the spacing at which the levers 15 and 12 are separated at the time of operation. At the termination of such relatively short cut, the gripping lever 10 is moved in a direction opposite the lever 12 20 for taking a new grip upon the rim 21 and the lever 12 again moved toward the anchoring lever 10 producing a further cutting by the blade 13. This is somewhat of a scissors operation with the abutments 19 and 22 20 acting as pliers for anchoring purposes and the end of the can may be easily and quickly cut through for its entire or partial circumference by repeating the cutting operations above noted in a step-by-step movement. The abutments 19 and 20 have their 30 inner adjacent faces beveled as at 19' and 20' respectively for assisting in obtaining a firm hold upon the rim 21. The form of the cutting knife 13 as illustrated in Fig. 6 35 of the drawing is such as to make a clean cut through the end of the metal can as well as ream both sides of the cut into a dull or turned over edge preventing the severed portions of the metal from injuring the hands of the operator.

While the form of the invention herein set forth is believed preferable it will be understood that changes may be made therein without departing from the spirit and scope of the invention.

What I claim as new is:—

1. A can opener comprising pivoted levers, one of said levers having a blade and a spaced abutment upon one face thereof, the other lever formed in two sections pivotally connected together, and abutments upon adjacent portions of said sections adapted for cooperating during movement of said levers toward each other.

2. A can opener comprising two levers, frictional pivotal connections between adjacent ends of said levers, one of said levers having a slot in its inner edge, a cutting blade removably secured in said slot, an abutment upon the slotted lever spaced from said blade when the device is assembled and holding means upon the other lever.

3. A can opener comprising two levers, frictional pivotal connections between adjacent ends of said levers, one of said levers

having a slot in its inner edge, a cutting blade removably secured in said slot, an abutment upon the slotted lever spaced from said blade when the device is assembled, the other one of said levers being formed in two sections pivotally connected together and abutments upon said lever sections at the same side of the device as the cutting blade adapted for movement toward and away from each other during operation of the levers toward and away from each other.

4. A can opener comprising two levers, pivotal connections between adjacent ends of said levers, one of said levers having a blade upon one face thereof, the other of said levers having means associated therewith for gripping the peripheral edge of a conventional type of can.

5. A can opener comprising a cutting lever and a gripping lever, the cutting lever provided with a cutting blade upon one face thereof and the gripping lever provided with means for rigidly gripping the annular flange of a conventional type of can.

6. A can opener comprising a cutting lever and a gripping lever, the cutting lever provided with a cutting blade upon one face thereof and the gripping lever provided with means for rigidly gripping the annular flange of a conventional type of can, the said gripping means being provided by forming the gripping lever into two sections, the adjacent edges of which have downwardly projecting gripping faces and wherein the adjacent edges of the two sections are pivoted together.

7. A can opener comprising a cutting member, a clamping member, pivotal connections between the cutting and clamping members, and means connected with the clamping member and operating to clamp the member to a can upon a relative movement of the cutting and clamping members about the pivotal connection.

8. A can opener comprising a cutter member, a gripper member, pivotal connections between the two members, and clamping means mounted upon the gripper member and designed to close upon and grip opposite sides of the upstanding bead of a can top upon relative movement of the two members about the pivotal connection.

9. A can opener comprising a cutting lever, a jointed gripping lever, pivotal connections between the cutting and gripping levers, and cooperating gripping members mounted upon the jointed gripping lever and designed to be moved into clamping relation upon a relative movement of the cutting and gripping levers about the pivotal connection.

10. A can opener comprising a cutting lever, a gripping lever, pivotal connections between the two levers adjacent the ends, cooperating abutments projecting down-

wardly from the gripping lever and adapted to engage at the inside and outside respectively of the peripheral edge of a can, the abutment engaging with the outside being 5 substantially longer than the inner abutment to project downwardly along the peripheral surface of the can, and means for moving the abutments into clamping relation upon relative movement of the two levers about 10 the pivotal connection.

11. A device for cutting sheet metal articles comprising a cutting member, a cooperating gripping member, connections between the cutting and gripping members, 15 and means associated with the gripping member for clamping the member with relation to the article to be severed by virtue of a pressure exerted upon the gripping member in a direction to impart a relative 20 movement to the cutting and gripping members whereby a relative movement may be imparted to the cutting member and sheet to be severed.

12. A can opener comprising cutting and 25 gripping levers, means for pivotally connecting the cutting and gripping levers, a blade carried by the cutting member, cooperating gripping devices carried by the gripping lever, and means for automatically 30 operating the gripping devices upon a relative movement of the two levers about the pivotal connection.

13. A can opener comprising cutting and gripping levers pivotally connected adjacent 35 the inner ends, a cutting blade carried by the cutting lever intermediate the ends, cooperating gripping devices carried by the gripping lever intermediate the ends, and means for causing the gripping devices to engage 40 with a can top and clamp the lever to the top upon a relative movement of the two levers about the pivotal connection in such a manner that the severing operation is accomplished by a progressive bodily movement 45 of the cutting and gripping levers about the circumference of the can top.

14. A can opener comprising a rigid arm carrying a cutter blade and a two-part arm

pivots connected to the first mentioned arm and fitted with a gripping device intermediately thereon to engage the rim of the can at the exterior and interior so that when the arms are moved relative to one another the can will be revolved in a direction to force the cutter blade through the can top 55 adjacent to the rim thereof.

15. A can opener comprising a rigid arm carrying a cutting device intermediately thereon and having its inner end overlying the can top, a link pivoted to the inner end 60 of the first mentioned arm and carrying a device to engage the flanged rim of the can top at the inside thereof, and an arm pivoted to the link and having its inner end engaging the can at the exterior of the rim where- 65 by when the two arms are moved relative to one another the rim of the can will be gripped and the can turned in a direction to force the cutting blade through the metal of the can top.

16. A can opener comprising pivoted levers, gripping and cutting instrumentalities mounted upon the levers, and means for causing the can to be intermittently gripped at its peripheral edge and a portion of the 70 top severed upon relative movement of the levers in one direction and the gripping devices to be released and advanced to a new gripping position upon relative movement of the levers in the opposite direction in 75 such a manner that the can is rotated and the top severed by a series of successive opening and closing movements of the levers.

17. A can opener comprising a cutting lever, a jointed gripping lever pivotally 80 connected therewith, gripping devices carried by the jointed lever designed to grip a can top upon relative movement of the levers about the pivotal connection, and a spring engaging with the two levers adja- 85 cent the pivotal connection and designed to retard the movement of the levers toward 90 one another.

In testimony whereof I affix my signature.

JOHN J. CHAPIN.
